UNITED STATES PATENT OFFICE.

GEORGE ANTHONY SINGERLY, OF PHILADELPHIA, PENNSYLVANIA.

DESIGN FOR A HORSESHOE.

SPECIFICATION forming part of Design No. 27,041, dated May 11, 1897.

Application filed April 1, 1897. Serial No. 630,308. Term of patent 14 years.

To all whom it may concern:

Be it known that I, GEORGE ANTHONY SINGERLY, a citizen of the United States, residing in the city and county of Philadelphia, 5 State of Pennsylvania, have invented and produced a new and original Design for a Horseshoe, of which the following is a specification, reference being had to the accompanying drawings, forming part thereof.

10 The leading feature of my design for a horse or animal shoe is a shoe having on the tread thereof depending segmental rims extending around the toe and heel portion thereof and necks intermediate of said portions on the upper part of the shoe alternating with the outer and inner members of the different rims.

15 Figure 1 represents a perspective view of a shoe embodying my design. Fig. 2 represents a section of the shoe on line xx , Fig.

1, and an elevation of the relative inner side 20 thereof.

A designates a horseshoe having on the tread thereof the segmental rims BB and CC, the rims B extending around the toe portions of the shoe and the rims C extending around the heel portions thereof.

D designates necks on the upper part of the shoe, the same being intermediate of the adjacent ends of the different rims B and C and alternating with the inner and outer 30 members of said rims.

What I claim is—

The design for a horseshoe substantially as described and shown.

GEORGE ANTHONY SINGERLY.
